OAR

Victor Ankarlo, Milwaukee, Wis., assignor of three per cent to R. C. Peterson, Duluth, Minn., and ninety-seven per cent to Hannah C. Ankarlo, Milwaukee, Wis.

Application March 2, 1933, Serial No. 659,262

3 Claims.

(Cl. 9—25)

This invention relates to certain new and useful improvements in oars.

It is an object of this invention to provide an oar having means embodied therein to obtain a mechanical advantage.

More specifically, it is an object of this invention to provide an oar comprising two sections geared together in such a manner that greater speed may be obtained with less effort.

10 It is also an object of this invention to provide an oar which permits the user to face the bow of the boat.

And a further object of this invention is to provide an oar of the character described which is of sturdy simple construction and readily adjustable to any type of boat.

With the above and other objects in view which will appear as the description proceeds, the invention resides in the novel construction, 20 combination and arrangement of parts substantially as hereinafter described and more particularly defined by the appended claims, it being understood that such changes in the precise embodiment of the hereindisclosed invention may be made as come within the scope of the claims.

In the accompanying drawings, one complete example of the physical embodiment of this invention is illustrated constructed according to the best mode so far devised for the practical application of the principles thereof, and in which:

Figure 1 is a top plan view of the conventional row boat equipped with oars constructed in accordance with this invention;

Figure 2 is a top plan view of the central portion of one oar;

Figure 3 is an enlarged view partly in section and partly in elevation, taken on the plane of the line 3—3 in Figure 2; and

Figure 4 is a detail perspective view of the connection for attaching the mounting structure of the oar to the boat.

Referring now more particularly to the accompanying drawings in which like numerals designate like parts throughout the several views, the 45 numeral 5 represents a conventional row boat having gunwales 6 to which the oars, indicated generally by the numeral 7, are attached.

Heretofore, with the conventional oars, the user was required to face the stern of the boat 50 and row backward, but this invention enables the occupant to face the bow of the boat which is obviously an advantage.

Each oar consists of a handle section 8 and a paddle section 9 pivotally mounted and geared 55 together, as at 10, so that pivotal movement of

one section is transmitted to the other section. The gear connection between the oar sections comprises two tubular members 11 and 12 into which the handle and paddle sections are respectively fitted. The adjacent ends of the tubular members have flat extensions 13 and 14 pivotally mounted on studs 15 and 16, respectively. The studs 15 and 16 are fixed to a supporting member 17 adapted to be attached to the gunwale of the boat in a manner to be hereinafter described. 10

Nuts threaded on the ends of the studs 15 and 16 readily detachably maintain the members 11 and 12 assembled with the supporting member.

At the meeting ends of the flat extensions 13 and 14, are meshing gear segments 18 and 19, 15 respectively, whereby pivotal movement of the member 11 is transmitted to as similar but opposite pivotal movement on the part of the member 12.

It is observed that the pitch radius of the segment 18 is substantially greater than that of the segment 19 so that the speed of the driven member 12 which carries the paddle section 9 is greater than that of the member 11 in which the handle section 8 of the oar is secured. This 20 permits the operator to manipulate the oars with a comparatively slow action which is obviously less tiring.

Through the transfer of motion from the large diameter gear segment 18 of the member 11 to 30 the small diameter segment 19 of the member 18, a loss in power is entailed, but this loss is offset by the increased speed of the paddle section. Moreover, as compared to the conventional oar which is mounted in an oar-lock carried directly 35 by the gunwale, there is not only an increase in the speed of the paddle section without necessitating a corresponding increase in the speed of manual actuation, but also a substantial increase in the effective force. This advantage is obtained by virtue of the fact that the pivots 15 and 16 are spaced a considerable distance out 40 from the gunwale.

The supporting member 17 is preferably a casting comprising a head 20 upon which the studs 45 15 and 16 are mounted, and an arm 21 extending therefrom to be attached to the gunwale of the boat. It is observed that the arm 21 is offset vertically with respect to the head 20, as at 22, to position the outer extremity of the arm in a 50 lower plane than the head 20 and afford greater clearance for the handle section.

A second arm 23 is pivotally connected, as at 24, to the supporting member. This arm 23 is also offset, as at 25, and is made adjustable with 55

respect to the arm 21 to accommodate boats of different shapes. The extremities of the arms 21 and 23 have clamps 26 attached thereto by which the arms are secured to the gunwales of the boat. The construction of these clamps, and the manner of their attachment to the arms is best illustrated in Figure 4.

Each clamp 26 has spaced yokes 27 and 28. The yoke 28 carries a screw 29, between the inner end of which and the face of the yoke 27 the gunwale is adapted to be clamped. An aperture 30 extending horizontally through the yoke 27 receives a cylindrical pin 31 forming part of a coupling 32 by which the clamp is attached to its arm. The cylindrical extension 31 being rotatable in the bore 30 obviously permits the clamp to be swung on the horizontal axis of the coupling.

The outer end of the coupling 32 is substantially oblong in shape and has a vertical bore 33. A correspondingly shaped opening 34 in the arm receives the oblong end of the coupling with its bore 33 aligning with a bore 35 in the arm. A pin 36 received in the aligned bores 33 and 35 serves to pivotally connect the coupling with the arm, and as the opening 34 is wider than the oblong end of the coupling, a degree of lateral movement is permitted between the coupling and the arm. In this manner, a substantial but freely adjustable connection is afforded between the arms and the boat, and while the structure shown is particularly well adapted to this purpose, other constructions obviously may be employed to afford the necessary adjustability to accommodate any type of boat.

It is particularly noted that the connection of the arms to the gunwale is such that the arms abut the outer faces of the gunwale to receive support directly therefrom.

Provision is also made for adjusting the length of the handle section 8 and paddle section 9 of the oars. This is readily accomplished in the manner illustrated in Figure 3, by providing a detent 37 carried by the round end of the paddle section and handle section and engageable in one of a plurality of openings 38 formed in the members 11 and 12 to readily releasably hold the oar sections in different positions of adjustment with respect to the members 11 and 12.

It is also noted that the tubular member 12 which carries the paddle section is inclined upwardly with respect to the plane of its gear segment. Consequently the sections of the oar are disposed at an angle to each other. This construction precludes dipping of the oar too deeply into the water and also facilitates making the return stroke.

In use, the operator faces the bow of the boat and actuates the oars in the conventional manner. The vertical tilting to dip the oars into the water and remove them from the water takes place about axes adjacent the gunwale of the boat and passing through the substantially universal mountings afforded by the connections of the clamps 26 with their respective supporting member arms. As already pointed out, the motion imparted manually to the handle sections of the oars is transferred to the paddle sections through their gear connections, and by virtue of the fact that the pivot points about which the sections

oscillate are positioned at a substantial distance from the gunwale of the boat and approximately midway in the total length of the oars, the effective force at the extremity of the paddle sections is but slightly less than that applied to the handle sections, the loss in applied force being entailed by the ratio of the gear segments.

However, even with a loss in force, the oars of this invention are far more efficient than the conventional type for not only is the effective resultant force greater, but also the speed of the paddle section is twice that of the handle section.

What I claim as my invention is:

1. An oar comprising a supporting member having a head and an arm rigid therewith, a second arm pivotally connected with the head portion for movement toward and away from the first arm, means carried at the extremities of the arms to readily detachably secure the same to the gunwale of a boat while permitting vertical tilting movement of the entire supporting member about an axis adjacent the gunwale, a handle section pivotally mounted on said head of the supporting member, a paddle section pivotally mounted on said head of the supporting member, and means carried by said sections to transmit motion from one to the other.

2. An oar comprising a supporting member having a head portion and an arm rigid therewith, a second arm pivotally connected with the head portion for movement toward and away from the first arm, clamps to attach the arms to the gunwale of a boat, means connecting the clamps with the outer extremities of the arms, said means having a substantial degree of universal adjustment to accommodate different angular dispositions of the gunwale, a pair of spaced pivot studs mounted on the head of the supporting member, a handle section pivotally mounted on one of said studs, a paddle section pivotally mounted on the other of said studs, and means carried by the sections to transmit motion from one to the other.

3. An oar comprising, a handle section, a paddle section, and means to operatively connect the handle section and paddle section and to mount the same from the gunwale of a boat, comprising a supporting arm, a substantially flat head formed as an integral part of the arm at one end thereof, a second arm pivotally connected with said head for movement toward and away from the other arm, means at the extremities of said arms to detachably secure the same to the gunwale of a boat, said attaching means enabling movement of said connected arms in a vertical plane about an axis directly adjacent the gunwale of the boat, means to pivotally mount the handle and paddle sections on said flat head, and means to drivingly connect said handle and paddle sections, the pivotal mountings of the handle and paddle sections precluding all relative movement between said sections and the said flat head and consequently the arms except the said pivotal movement whereby vertical force applied to the handle section causes the entire mechanism to tilt vertically about the axis adjacent the gunwale of the boat.

VICTOR ANKARLO.
